UNITED STATES PATENT OFFICE.

JOSEPH WILHELM AND CHARLES A. KAYS, OF MCKEES ROCKS, PENNSYLVANIA.

FILM-REEL.

1,353,004.

Specification of Letters Patent. Patented Sept. 14, 1920.

Application filed August 14, 1919. Serial No. 317,411.

To all whom it may concern:

Be it known that we, JOSEPH WILHELM and CHARLES A. KAYS, citizens of the United States, residing at McKees Rocks, in the county of Allegheny and State of Pennsylvania, have invented certain new and useful Improvements in Film-Reels, of which the following is a specification.

This invention relates broadly to film reels and more particularly to new and useful improvements in the hub construction.

The primary object of this invention is to provide a hub of the type set forth and in a manner as hereinafter described, which has a detachable and replaceable clamping member for engaging the end of the film, adapted to be wound on the hub, thereby permitting the replacement of the clamping member when broken in use and thus eliminating the necessity of discarding or scrapping the entire reel, as is now required by reels of the construction commonly in use.

Further objects of this invention are to provide a device of the character described, which is simple in its construction and arrangement, strong durable and efficient in its use, and comparatively inexpensive to manufacture.

To the accomplishment of these and such other objects as may hereinafter appear, the invention consists of the novel construction, combination and arrangement of parts herein specifically described and illustrated in the accompanying drawing, wherein is shown an embodiment of the invention, but it is to be understood that changes, variations, and modifications may be resorted to which come within the scope of the claims hereunto appended.

40 In the drawing forming a portion of this specification and wherein like numerals of reference designate corresponding parts throughout the several views:

Figure 1 is an end view of a film reel in accordance with this invention and illustrating the manner of securing the end of a film thereto.

Fig. 2 is a cross sectional view on line 11—II. Fig. 1.

50 Fig. 3 is a cross sectional view on line III—III, Fig. 1.

Fig. 4 is a perspective view of the clamping member.

Referring more in detail to the drawing,

there is shown in Fig. 1 a film reel comprising the hub 1 and the disks 2 and 3, respectively.

The hub 1 is preferably constructed from sheet metal, formed cylindrically, and is provided on its outer edges with integrally formed lugs 4, adapted to be clenched upon the outer face of the respective disks 2 and 3, which are provided with suitable slots 5 for the passage of the lugs 4 and for the purpose of permanently securing the disks 2 and 3 to the hub 1.

The hub 1 is provided with a transversely extending slot 6, disposed approximately centrally thereof. The hub 1 is further formed with the gradual depression 7, the lowest point 8 thereof forming the forward edge of the slot 6, and with the gradual elevation 9, the highest point 10 thereof forming the rear end of the slot 6.

A clamping tongue 11, made from spring metal and of less width than the width of the slot 6, extends through said slot and has its rear end secured or riveted, as at 12, to the inner side of the elevation 9, formed in the hub 1. The forward end of the clamping tongue 11 is positioned to extend over the outer side of the depression 7, and adjacent its end is curved downwardly, as at 13, while the extreme end 14 is curved slightly upwardly.

The removable clamping spring 15, shaped and adapted for circumferentially engaging the hub 1, is formed with the centrally disposed inset portion 16 forming a seat for the reception of the clamping tongue 11, which is adapted for detachably securing the spring 15 to the hub 1. The ends 17 and 18, of the clamping spring 15, are curved slightly outwardly to facilitate the attachment of the end of the film 19 thereunder.

It will be obvious that the construction of the depression 7, in the hub 1, in conjunction with the curved end 14, of the clamping tongue 11, will readily permit and facilitate the insertion of the clamping spring 15, while the curvature, as at 13, will assure the retention of the spring 15 by the clamping tongue 11.

The clamping tongue 11, being of less width than the width of the slot 6, the inset portion 16 of the clamping spring 15 will depend therein and be engaged by the longitudinal edges of the said slot and prevent

liability of circumferential movement of the spring 15 when the inset portion 16, thereof, is seated under the clamping tongue 11.

It will here be noted that the utility of a film reel constructed with a hub in accordance with this invention is not impaired if the clamping spring 15 is broken, as the latter may readily be replaced by another without inconvenience to the operator.

10 From the foregoing description taken in connection with the accompanying drawing, the advantages of the construction and the method of operation will be readily apparent to those skilled in the art to which the invention appertains, and while describing the principle of operation of the invention together with the device which is now considered to be the best embodiment thereof, it is to be understood that the device shown is 15 merely illustrative and that various changes in the form, proportion and the minor details of construction may be resorted to without departing from the principle or sacrificing any of the advantages of the invention 20 as defined in the appended claims.

What we claim is:

1. A hub for film reels comprising a cylindrical body portion, a resilient clamping tongue extending transversely of said body portion, said tongue having its inner end secured to the inner face of the body portion and further having a part thereof arranged within the body portion and the remaining part thereof positioned against the 30 periphery of the body portion, and a removable clamping member positioned under said clamping tongue.

2. A hub for film reels comprising a cylindrical body portion, a clamping member extending circumferentially of said body portion, and a transversely extending resilient clamping tongue for detachably clamping the said member to said body portion, said body portion being slotted and said tongue 40 extending through the slot and having its inner end secured to the inner face of the body portion and said tongue further having its outer end arranged over the periphery of the body portion.

3. A hub for film reels comprising a cylindrical body portion, a removable clamping member having an inset portion extending

circumferentially of said body portion, and a resilient clamping tongue carried by said body portion and engaging said inset portion for detachably connecting said member to said body portion, said body portion being slotted for the reception of the inset, said tongue extending through said slot and having its inner end secured to the inner face 55 of the body portion.

4. A hub for film reels comprising a cylindrical body portion provided with a slot, a clamping member having an inset portion and extending circumferentially of said body, said inset portion adapted to seat in said slot, and a transversely extending resilient clamping tongue carried by said body for detachably securing said member to said body by engaging said inset portion in said slot, said tongue extending through said slot and having its inner end secured to the inner face of the body portion and its outer end arranged over the periphery of the body portion.

5. A hub for film reels comprising a hollow cylindrical body portion provided with a transverse depression gradually increasing in depth from one end to the other, said body portion further provided with a slot at the 80 lowest point of said depression, a resilient and transversely extending clamping tongue extending through said slot and having its inner end secured to the inner face of the body portion and its outer part arranged 85 over said depression, and a circumferentially disposed clamping member having an inset portion extending in said slot and engaged by the tongue whereby said member is detachably secured in position.

6. A hub for film reels comprising a body portion provided with a slot, a clamping tongue disposed transversely with respect to said body portion and extending through said slot and having its inner end fixedly secured to the inner face of the body portion, and a clamping member having an inset portion extending in said slot and engaged by the tongue whereby said member is detachably secured in position.

In testimony whereof we affix our signatures.

JOSEPH WILHELM.
CHARLES A. KAYS.
